UNITED STATES PATENT OFFICE.

WILLIAM LOFT, OF JERSEY CITY, NEW JERSEY.

DESIGN FOR A CANDY-TRAY.

SPECIFICATION forming part of Design No. 16,213, dated August 25, 1885.

Application filed April 27, 1885. Term of patent 7 years.

To all whom it may concern:

Be it known that I, WILLIAM LOFT, a citizen of the United States, residing in Jersey City, in the county of Hudson and State of New Jersey, have invented and produced a new and original Design for Candy-Trays, of which the following is a specification, reference being had to the accompanying drawing, forming part thereof.

10. The drawing is a plan view of my design for a candy-tray.

The novel features of my design consist in the shape and configuration of the article herein shown and described.

1. I represent in the drawing a tray of rectangular shape, and divided to represent smaller rectangular compartments and a long rectangular compartment, the latter being at one side. Within each of the smaller compartments is the representation of two scalloped circular figures, one within the other. Within the long compartment are spoon-shaped figures.

Having thus described my invention, the following is what I claim as my production and desire to secure by Letters Patent:

1. The design for a candy-tray herein shown and described, the same consisting of a rectangular frame having smaller rectangular compartments, and inner and outer scalloped circular figures within each compartment.

2. The design for a candy-tray herein shown and described, the same consisting of a rectangular frame, having smaller rectangular compartments and a long rectangular compartment at one side, and inner and outer scalloped circular figures within each smaller compartment.

In testimony whereof I have hereunto set my hand this 25th day of April, 1885.

WM. LOFT.

In presence of--

R. F. VAN BOSKERCK,
CHARLES G. COE.
